UNITED STATES PATENT OFFICE.

WILLIAM E. EASTMAN, OF BOSTON, MASSACHUSETTS.

FEED-REGULATOR FOR OIL-STOVES.

SPECIFICATION forming part of Letters Patent No. 308,955, dated December 9, 1884.

Application filed November 8, 1883. (No model.)

To all whom it may concern:

Be it known that I, WILLIAM E. EASTMAN, a citizen of the United States, residing at Boston, in the county of Suffolk and State of Massachusetts, have invented certain new and useful Improvements in Feed-Regulators for Oil-Stoves, of which the following is a specification, reference being had therein to the accompanying drawings.

10 The object of my invention is to provide a reliable automatic feed-regulator, particularly for oil-stoves to be used as heaters for freight-cars, for which the following-named United States patents have been granted to myself and associates, to wit: No. 247,028, No. 248,924, No. 253,521, and No. 269,189; but it is also applicable to oil-stoves for heating other moving vehicles, or for heating rooms, or for cooking. The reservoir of oil or other liquid fuel 15 may be placed at a higher level than the fire, and thus feed by gravity; or it may be placed at a lower level than the fire and feed by pressure, as compressed air in a closed tank above the liquid. The latter method is preferable 20 for feeding stoves for heating or cooking in stationary structures, as the reservoir can be located in the cellar.

The construction of my devices is shown in the accompanying drawings, in which—
30 Figure 1 is a perspective view of an oil-stove with the regulator attached. Fig. 2 is an enlarged sectional view of the regulator. Fig. 3 shows in section that portion of the regulator carrying a screw-valve for cutting off entirely the flow of fuel to the stove; and Fig. 35 4 is perspective view of the valve proper, showing the grooves *i* and *k*, hereinafter more fully explained. Fig. 5 is an enlarged section representing the valve and valve-case, with a per-
40 manently-open passage through the latter for the continuous flow of the liquid fuel from the supply-tank to the burner. Fig. 6 is a similar section representing the permanently-open passage through the valve, that through the 45 valve-case being omitted.

The same letters of reference indicate like parts in the several views.

A is a tube, of brass or other highly-expansible metal or alloy, which is attached rigidly 50 to the dome *C*.

Within the tube *A* is a rod or tube, *B*, of

iron or other metal or alloy less expansible by the heat than the tube *A*. This inner rod or tube, *B*, is connected to the tube *A* at or near the free end of the latter by a threaded cap or head 55 engaging with a screw-thread cut in the inner surface of the tube *A*, as is clearly shown in the drawings. The outer end, *b*, of this cap or head *a* is made square in cross-section, or preferably of an irregular form, so as to be 60 turned only by the special key *K*, for reasons hereinafter fully explained. The other end of the rod or tube *B* touches and by differential expansion of the pair operates the diaphragm *d*, which is soldered or otherwise 65 properly attached at its periphery to the under side of the dome *C*. The dome *C* is screwed down into the valve-case *D*, so as to make an oil-tight joint, and the ring *e* is 70 screwed down upon it to act as a check-nut.

Under the diaphragm *d* is the valve *E*, which by its movements regulates the flow of fuel to the stove. A lower valve-seat, *f*, is formed in the valve-case *D*, and an upper valve-seat, *e*, is formed by a recess in the ring *o*, which 75 ring is screwed down in the recess, a part of which forms the lower valve-seat, *f*. The stem of the valve *E* passes loosely through this ring *o*, and as the recess in the ring is somewhat larger than the diameter of the valve the oil 80 can freely pass when the valve is not seated.

Upon the upper side of the valve *E* is the small groove *i*, and upon the lower surface a similar groove, *k*, as shown in Fig. 4.

Below the valve *E* is a cylindrical chamber 85 containing the follower *h* and the spring *g*. The follower is always forced up against the valve by the spring, the constant tendency being to carry the valve to its upper seat, *e*. The inlet *m* enters this chamber, while the outlet *n* 90 leads from the space above the valve and below the elastic impervious diaphragm *d*. When occasion requires, the flow of fuel to the stove is entirely prevented by closure of the screw-valve *p*. (Shown in section in Fig. 3.) 95 Wings upon the under side of the valve *E* fit closely in the chamber below the valve and prevent lateral movement.

The use of the impervious elastic diaphragm *d* is a necessity when the fuel is to be fed under artificial pressure; but it may be omitted if the pressure is due merely to gravity from

a reservoir whose highest point is not higher than the top of the tube A.

- The operation of my device is as follows: When the temperature of the surrounding air 5 is low, the contraction of the unequal-expansion pair A B, acting upon the valve E through the diaphragm d , forces the valve firmly upon its lower seat, f . If, now, the screw-valve p be opened, so much liquid fuel only as can 10 pass through the groove k will flow through (or around) the valve; but this quantity will be sufficient to start the fire. As the heat of the stove increases, the pair A B, by expansion, will relieve the valve somewhat from the 15 pressure upon it and allow the spring g to move it upward toward its upper seat, e , increasing the flow of fuel. The largest quantity will flow when the valve is just half-way between its seats, and consequently any fur- 20 ther expansion of the pair A B will diminish the flow of fuel. The flow, however, can never be entirely stopped, as the groove i , when the valve is fully upon its upper seat, will always allow a small quantity to pass.
- 25 It will be seen that during one part of the movement of the valve from one of its seats to the other an increase of heat will increase the flow of fuel, while during the remainder of the movement an increase of heat will diminish 30 the flow. The movement of the valve, how- ever, when the fire is well started, is confined between the midway position and the upper seat.
- The adjustment of the iron rod or tube B 35 within the brass tube A is found to be one requiring great care and considerable experience, and for this reason the longitudinal movement obtained by screwing the same in or out is arranged, as before stated, to be ef- 40 fected only by a special key, K. This is es- pecially necessary when the device is used upon moving vehicles, as it is likely to be tampered with by unskilled persons whose at- tempts at adjustment would almost certainly 45 be disastrous.
- The grooves i and k serve, as already ex- plained, to prevent entire stoppage of the flow, no matter upon which seat the valve is; but the same result may be obtained by a small 50 hole, i^2 , passing entirely through the valve, or from the chamber below the valve through the substance of the valve-case to the space above the valve, or by any other suitable equivalent device.
- 55 Instead of using a single valve having two seats, as described, I may employ two valves, each having an independent seat—for instance, two valves may be secured to or operated by the opposite ends of a lever having an inter- 60 posed fulcrum, one valve being seated while

the other is unseated; but I prefer the construction shown and previously described, as thereby I economize space.

Instead of a continuously - open passage through the valve-case, as shown in Fig. 5, 65 an open passage through the valve may be formed, as shown in Fig. 6, the grooves i and k in the valve and the passage in the valve- case in such construction being omitted.

Having thus fully described my invention, 70 I claim the following:

1. The unequal-expansion pair or "combi- 75 nation" A B, the valve E, having a perma- nently-open passage, a valve-case having two seats, e f , combined, constructed, and ar- ranged in such manner that the flow of fuel will be increased by an increase of the tem- perature of the pair or combination when be- 80 low a predetermined degree, and be decreased by the increase of the temperature of the pair or combination when above said predeter- mined temperature, for the purpose specified.

2. An automatic feed - regulator for oil- 85 stoves, consisting of a two-seated valve actu- ated in one direction by the differential ex- pansion of an unequal-expansion pair; and in 90 the opposite direction by the expansion of a spring, in combination with a permanently- open passage for preventing the entire stop- page of the flow of the fuel to the burner when the valve is upon either seat, for the purpose set forth.

3. A spring-actuated two-seated valve, an 95 unequal-expansion pair or combination for controlling the same, and a device for regu- lating the adjustment of the expansion pair or combination, as and for the purpose speci- fied.

4. The unequal-expansion pair A B, in com- 100 bination with the valve E, having its upper and lower surfaces each provided with a groove, the valve-seats e f , and the spring g , for the purpose described.

5. A liquid-fuel heater, an unequal-expa- 105 sion pair A B, an elastic impervious dia- phragm, d , a double-seated spring-actuated valve, E, with its grooves i k , combined and constructed to operate as and for the purpose specified.

6. The follower h , spring g , valve E, with 110 its grooves i k , the valve-seats e f , and the dia- phragm d , in combination with an unequal- expansion pair, A B, as set forth.

In testimony whereof I affix my signature in presence of two witnesses.

WILLIAM E. EASTMAN.
